UNITED STATES PATENT OFFICE.

WILLIAM M. AMMERMAN, OF OAKLAND, ILLINOIS.

MECHANICAL MOVEMENT.

SPECIFICATION forming part of Letters Patent No. 290,383, dated December 18, 1883.

Application filed October 18, 1883. (No model.)

To all whom it may concern:

Be it known that I, WILLIAM M. AMMERMAN, a citizen of the United States of America, residing at Oakland, in the county of Coles 5 and State of Illinois, have invented certain new and useful Improvements in Mechanical Movement; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to certain new and useful improvements in mechanical movement, its object being to provide a means whereby a continuous rotary motion will be converted into an intermitting rotary motion, 20 which may be readily converted again into a reciprocating motion, so as to provide a means which may be readily attached and utilized in many different classes of machinery.

25 For the purpose of illustrating my invention, I have shown the same applied to a check-row corn-planter, which corn-planter, aside from the improved mechanical movement, possesses certain novel features, as will be hereinafter more fully set forth, and are illustrated 30 in the accompanying drawings, in which—

35 Figure 1 is a plan view, showing one manner of applying my invention. Fig. 2 is a sectional view of my improved means for converting the continuous rotary motion into an intermitting reciprocating motion. Fig. 3 is a detailed perspective view. Fig. 4 is a plan view of the cord-tightener which is employed when my improvement is used upon a check-row corn-planter, and Fig. 5 is a detail of the 40 edge of the driving-wheel.

45 A represents the frame of a corn-planter which is provided with seed-boxes B B, which are supported upon a transverse bar or beam, the center portion of the frame being provided with a transverse axle and driving-wheels, as shown, to the rear of which is secured the driver's seat in the usual manner.

At the end of the beam C, which supports the seed-boxes, are pulleys a a, over which 50 passes a cord or wire, b, which is guided by

means of the spring-pulleys c c' around the driving-wheel D, which driving-wheel is concave or wedge-shaped at its rim, as shown at d in Fig. 5, said concave or V-shaped groove being provided alternately on opposite sides 55 with triangular blocks b', which bite the cord and prevent the same from slipping in the groove.

The pulleys c c', hereinbefore referred to, are mounted upon springs C', which will take up the slack of the cord and tighten the same in the rim of the wheel. This driving-wheel is also provided with a spring-catch, e, which has a downwardly-extending portion, e'. This spring-catch will bind upon the cord and hold 65 the same from slipping.

By means of a raised portion or block, E, upon the frame this spring-catch is caused to open at each revolution of the driving-wheel B as the cord enters the grooved rim of the 70 same, and is opened as the cord passes from said groove.

By the means hereinbefore described it will be seen that a positive motion is given to the driving-wheel D, though in other styles of 75 machinery this wheel may be rotated by other positive means. The shaft F, to which the driving-wheel is rigidly attached, is provided at a suitable point with a wheel or disk, which wheel or disk has cut in its periphery two inverted quadrantal arcs or grooves, as indicated by the letters f f', above which is secured or formed upon the wheel a block in the shape of a pelecoid, the upper portion or part above or to the side of the grooves, according to the 85 position of the disk G, being curved. By this construction I provide the two grooves f f'. Opposite this wheel or disk G, so as to extend at right angles with the axis of the same, is a shaft, H, which is provided at its ends 90 with a yoke, h, which yoke has two outwardly-projecting pins, h h'.

The end of the shaft H may be provided with an arm, as shown in Fig. 1, or other means for transmitting motion.

In Fig. 1 I have shown a crank-shaft, which is attached directly to the seed-slides.

The operation of my improved means for converting motion may be described as follows: When the driving-wheel D is rotated, it car- 100

ries with it the disk E, and when the portion of the disk provided with the grooves hereinbefore described comes in contact with the pin h', nearest the same, said pin enters the 5 groove and passes in said groove below the portion g, thus causing the shaft h to make one-half of a complete turn. The same pin which enters the groove is then forced upward by the next arc, and when the pin leaves said 10 arc the shaft has made a complete revolution, and the pins upon the yoke will lie adjacent to the periphery of the wheel.

It is evident that the same movement will be accomplished whether the wheel G is turned 15 either to the right or left, and if it is desired to give the shaft H more than a single intermitting rotary movement with respect to the disk G, said disk may be provided with two or more grooves and block similar to that 20 hereinbefore described.

As both the pins upon the yoke h rest upon the surface of the disk G, the shaft will be prevented from rotating except when the pins come in contact with the grooves.

25 The arm upon the upper portion of the block may serve as the guide to one of the pins while it is passing over the curved portion, the other pin being within one of the grooves.

Having thus described my invention, what

I claim as new, and desire to secure by Letters 30 Patent, is—

1. In a device for converting motion, a driving-wheel and shaft provided with two inverted quadrantal grooves, in combination with a shaft provided with projecting pins, for the 35 purpose specified.

2. As a means for converting a continuous rotary motion into an intermittent rotary motion, the disk or wheel G, provided with grooves f f' and curved projecting portion g, and shaft 40 H, having projecting pins h, the parts being organized and combined substantially as shown.

3. In combination with the driving-wheel D, provided with a groove and catch for the purpose of retaining a cord and spring tension 45 devices, the wheel G, with inverted arc-shaped grooves, and shaft H, provided with projecting pins, said shaft having attached thereto means whereby the intermittent rotary motion of said shaft will be converted into a reciprocating motion, the parts being organized substantially as shown.

In testimony whereof I affix my signature in presence of two witnesses.

WILLIAM M. AMMERMAN.

Witnesses:

H. P. RITCHIEY,
JOHN F. MENAUGH.
